UNITED STATES PATENT OFFICE.

FRANK KOPERSKI, OF BAY CITY, MICHIGAN, ASSIGNOR OF ONE-THIRD TO KASIMAR E. NIEDZIELSKI, OF BAY CITY, MICHIGAN.

ROCKING BABY-CARRIAGE.

1,174,257.

Specification of Letters Patent.

Patented Mar. 7, 1916.

Application filed August 4, 1915. Serial No. 43,628.

To all whom it may concern:

Be it known that I, FRANK KOPERSKI, a citizen of the United States of America, residing at Bay City, in the county of Bay and State of Michigan, have invented certain new and useful Improvements in Rocking Baby-Carriages; and I do hereby declare the following to be a full, clear, and exact description of the invention, such as will enable others skilled in the art to which it appertains to make and use the same.

This invention relates to a mechanism for rocking baby carriages, cribs, and the like.

It is the object and purpose of this invention to provide a mechanism and connect it with a crib construction in such manner as to cause a rocking movement of the crib, said mechanism being of very simple construction and operation.

20 A further object of the invention is to apply the same mechanism to a baby carriage and to construct the carriage so that the body thereof may be elevated above its usual supports and supported in the same 25 manner as the movable portion of a crib, the body of the carriage thereafter being capable of rocking movement the same as a crib.

The construction by which these ends are 30 attained is fully shown in the accompanying drawings, in which;

Figure 1 is a side elevation of a baby carriage with my invention applied thereto. Fig. 2 is a vertical section taken on the line 35 2—2 of Fig. 3. Fig. 3 is an elevation of an attachment connected at each end of the carriage. Fig. 4 is a plan view of the frame of the carriage and illustrating in plan the mechanism for elevating the body thereof.

40 Fig. 5 is a side elevation of the construction shown in Fig. 4. Fig. 6 is a rear elevation thereof. Fig. 7 is a plan view of the motor casing containing the motor for operating the carriage or cradle. Fig. 8 is an elevation of said casing. Fig. 9 is a sectional and plan view on the line 9—9 of Fig. 10, looking in the direction indicated by the arrows. Fig. 10 is a front elevation of a cradle with the rocking mechanism applied thereto; and 50 Fig. 11 is an end view thereof.

Like reference characters refer to like parts throughout the several views of the drawings.

The body of the carriage is indicated at 1 being supported on the usual springs 2 55 which are secured to the cross rods 3 serving as axles to the carriage and on the ends of which are rotatably mounted the wheels 4 in the usual manner. A frame including spaced apart rods 5 is provided, said rods 60 extending horizontally from the front to the rear axle and being thence bent upwardly and to the rear as indicated at 6 forming the handles by which the carriage is manually moved from place to place. The construction thus far described is the usual carriage construction in devices of this character.

At both the front and rear ends of the body 1 an open ended housing 7 is secured 70 having a horizontal rod 8 supported adjacent its upper end from which depends a bar 9, its lower end inserting into the tubular member 10. A rod 11 is rigidly secured to member 10 and extends downwardly being divided into two parts as shown at 12, which are bent forwardly and secured to the forwardly projecting arms 13 of a pair of bell crank levers pivotally mounted on the axle 3. It is of course understood that a 80 construction including 7 and members 10, 11 and 12 is located at both the front and rear of the carriage body and that both the front and rear axles 3 are supplied with two spaced apart bell crank levers having the 85 forward projecting arms 13 and also vertical arms 14 which are connected together by rods 15 substantially parallel to the axles 3. A bar 16 extends between and is connected at its ends to the rods 15. The tubular members 10 are supported in this manner by the members 11 from the arms 13 of the bell crank levers and at a short distance below the lower ends of bars 9 pins 10^a extend through the tubular members 10 as shown. 90

95 An arm 17 is connected at its upper end to the rod 15 lying between the upwardly extending arms 14 of the rear bell crank levers, at its lower end having attachment to a pedal 18 which is pivotally mounted at 100 its forward end to the rear axle 3, extending a distance to the rear thereof. By pressing on the pedal 18 all of the bell crank levers connected together in the manner described are simultaneously operated to the rear 105 about the axles 3, thereupon elevating the

ends of the forwardly extending arms 18 and simultaneously causing the pins 10^a to strike against the ends of bars 9 whereupon the carriage body is lifted above springs 2 and supported by the horizontal rods 8 at the upper ends of bars 9, it being evident that the body will then be pivotally mounted on a horizontal axis and permitted to swing about said axis.

- 10 Supported from the handles 6 is a casing 19 in which may be inclosed any suitable spring motor or other mechanism for operating the upwardly extending bar 20 back and forth through an arc of a circle. Motors of this type are of conventional design and the specific construction of this motor forms no part of the present invention but is fully disclosed in a separate application. Arm 20 extends through a slot 21 in the upper side of the casing 19 and has its end bent forward at right angles and pivotally connected to the rear end of a member 22 as shown at 23. The member 22 is supported at the upper end of a post 24 carried by the frame of the carriage being loosely mounted thereon to turn about a vertical axis. A pin 25 is attached to and projects downwardly from the bottom of the body 1 passing through a slot 27 in the member 22. It will be clear that with the oscillatory movement of the arm 20 back and forth as indicated in dotted lines in Fig. 8 the forward end of member 22 is correspondingly actuated back and forth about its pivotal mount at the upper end of the post 24 and that the body of the carriage after its elevation above the springs 2 is given a rocking movement about its pivotal supports at 8 as long as the motor within the casing 19 is running. When the carriage is to be used in the usual manner the body may be lowered until it again rests on the springs 2 whereupon the rocking movement of the body cannot be made to take place and will not take place until it is again elevated.

15 The same mechanism is adapted to be used with the crib shown in Figs. 10 and 11. A body 28 is mounted between the uprights 29 on the pins 30, the uprights being permanently connected together by a cross-beam 31 and at their lower ends having the outwardly extending supporting arms 32 normally resting upon a floor. The motor casing 19 is attached to one of the uprights 29 while the post 24 is carried by the beam 31. Parts 20, 22, 23 and 25 in the crib construction are identical with the parts similarly numbered and heretofore described with reference to the baby carriage and the rocking movement of the crib is exactly the same as that of the carriage when it is elevated above the springs 2.

20 Various modifications in detail and in form, proportions and the like may be resorted to without departing from this in-

vention which is defined in the appended claims and which includes all modifications of structure falling within their scope.

I claim:

1. In combination, spaced apart supports, 75 a body pivotally mounted on a substantially horizontal axis between the supports, a pin extending downwardly from the body, a bar pivotally mounted between its ends to turn about a vertical axis located below the body 75 and having one end engaging with the pin, and means at the other end of the bar connected therewith for operating it back and forth about its pivotal mount.

2. In combination, spaced apart supports, 80 a body pivotally mounted on a substantially horizontal axis between the supports, a pin extending downwardly from the body, a bar pivotally mounted between its ends to turn about a vertical axis located below and 85 lengthwise of the body, one end thereof engaging with the pin, and a motor having an upwardly extending arm movable back and forth through an arc of a circle located at the other end of and below the bar, the arm 90 being pivotally connected to said end of the bar.

3. In combination, a vehicle including a body, a relatively fixed support on which the body is adapted to rest, means to elevate 95 the body above said support and suspend it at its ends on horizontal pivots, and means to rock the body back and forth about said pivots, substantially as described.

4. In combination, a vehicle including a 100 body, a relatively fixed support on which the body is adapted to rest, horizontal pins projecting from either end of the body, upright supports connected thereto, means to elevate said upright supports to thereby elevate the body above its relatively fixed support and suspend it by said pins for rocking movements, a motor and means interposed between the motor and body for rocking the body back and forth on operation of the 110 motor.

5. In combination in a vehicle, a frame including spaced apart front and rear axles, spring members supported above the frame, a body normally resting on the spring members, bell crank levers having vertical and horizontal arms pivotally mounted on each axle, connections between the vertical arms, substantially upright supports carried at the ends of said horizontal arms, horizontal 115 pins extending from the ends of the body passing loosely through the upper ends of the upright supports, means to operate the bell crank levers to elevate the body above the spring members, and means to rock the body back and forth after the elevation thereof, substantially as described.

6. In combination in a vehicle, a frame including spaced apart front and rear axles, spring members supported above the frame, 130

a body normally resting on the spring members, bell crank levers having vertical and horizontal arms pivotally mounted on each axle, connections between the vertical arms, 5 substantially upright supports carried at the ends of said horizontal arms, horizontal pins extending from the ends of the body passing loosely through the upper ends of the upright supports, means to operate the bell crank levers to elevate the body above the spring members, a pin extending downwardly from the bottom of the body, a

motor carried by the frame having an upwardly extending arm movable back and forth through an arc of a circle, a bar located horizontally and pivotally mounted between its ends on a vertical pivot, said bar having connection at one end to the arm and at the opposite end engaging with the pin, substantially as described. 15

In testimony whereof I affix my signature. 20

FRANK KOPERSKI.
